UNITED STATES PATENT OFFICE

96,665

DESIGN FOR A BLOUSE

Max G. Haley, Plymouth, N. H., assignor to White
Mountain Manufacturing Company, Plymouth,
N. H., a corporation of New Hampshire

Application December 17, 1934, Serial No. 54,454

Term of patent 3½ years

To all whom it may concern:

Be it known that I, Max G. Haley, a citizen of the United States of America, residing at Plymouth, county of Grafton, State of New Hampshire, have invented a new, original, and ornamental Design for a Blouse, of which the following is a specification, reference being had to the accompanying drawing, forming a part thereof.

In the drawing:

The figure of the drawing is a front view of a blouse, embodying the design, the characteristic feature residing in the arrangement of the muff, which is permanently attached to the blouse, thus forming an integral part thereof.

I claim:

The ornamental design for a blouse, substantially as shown and described.

MAX G. HALEY.
